(57) **CLAIM**

The ornamental design for a race car, as shown and described.

DESCRIPTION

FIG. 1 is a front perspective view of a race car, illustrating the novel design;

FIG. 2 is a rear perspective view of the race car design of FIG. 1;

FIG. 3 is a front view of the race car design of FIG. 1;

FIG. 4 is a rear view of the race car design of FIG. 1;

FIG. 5 is a left side view of the race car design of FIG. 1;

FIG. 6 is a right side view of the race car design of FIG. 1; and,

FIG. 7 is a top view of the race car design of FIG. 1.

The broken lines shown in the drawings illustrate portions of the race car that form no part of the claimed design.

1 Claim, 6 Drawing Sheets
